UNITED STATES PATENT OFFICE

GEORGE E. TEASDALE, OF KANSAS CITY, KANSAS

LUMINESCENT TUBE

Application filed May 4, 1929. Serial No. 360,446.

My invention relates to illumination by luminous tubes of glass containing rare atmospheric gases, such, for instance, as neon gas which becomes luminescent by the passage therethrough of high voltage electric currents introduced into the gas through electrodes located in the ends of the tube. The electrodes are in direct contact with the gas and connected to the inner ends of terminal wires which extend outwardly through the ends of the tube and are connected to the two sides of a high voltage circuit.

When the high voltage is applied to the electrodes, the neon gas in the tube acts as a conductor and becomes brilliantly illuminated, giving off a bright orange red color which makes it very desirable for advertising and other commercial purposes, especially when the tubes are formed into letters, numbers and various other designs.

Difficulty in the manufacture of the tubes has been experienced because regardless of how pure the gas was when introduced into the tube, when illuminated, it became badly discolored from impurities thrown off by the electrodes and the impure active gases present in the air within the tube. In order to overcome the foregoing difficulty the air existing in the tube prior to the introduction of the neon was exhausted to a high state of vacuum, but in spite of the precautions which were taken to introduce extremely pure neon into the tubes, and of the care taken in exhausting the air from said tubes, nevertheless, impurities would appear when the neon was illuminated as the electrodes and the glass walls of the tubes, absorb and hold on their exposed surfaces impurities such as the active foreign gases, and when heat is applied to those surfaces they yield up these foreign gases, which are known in the art as "occluded gases." It was found necessary to remove enough of these gases from the electrodes and walls of the tube by subjecting the latter to a current in excess of normal so that when the tubes are placed in commercial use no more occluded gases will be driven out of these parts due to such heating as takes place during normal operation.

It was also discovered that notwithstanding the liberation of the active gases occluded in the electrodes and walls during the formation of the tubes, impurities were still present after the neon was introduced. 55 These gases have hitherto been removed by attaching to the tube a receptacle containing powdered cocoanut charcoal which, when reduced to an extremely low temperature by immersing the receptacle in liquid air, absorbs the impure gases and leaves the neon in an approximately pure state. 60

After the neon in the tube had thus been purified it was found that there was another serious difficulty in the way, for although the tube had attained the characteristic neon color, its life was relatively short compared with that of an incandescent lamp which averaged one thousand hours, whereas it was desired to produce a neon 70 tube in which one introduction of neon gas would yield a life much longer than that of the incandescent lamp.

Experimentation developed the fact that the short life of the tube was attributable to a phenomenon connected with the electrodes known as "vaporization" or "sputtering." In the presence of the rare gases such as neon, the sputtering of the electrodes was very pronounced particularly when the electrodes had a surface area of less than 1.5 square decimeters per ampere, said sputtering being caused by a drop in potential or voltage from the electrodes to the point where the luminous part of the gas appears and causes the electrodes to become highly heated. The high temperature causes the electrodes to sputter at a high rate so that particles of material composing the electrode are thrown off and deposited on the glass walls of the tube in which the electrodes are located. As the particles of material are thrown off they carry and pocket a certain quantity of the neon gas against the glass walls. This pocketing causes so much of the gas to be used up and its pressure so reduced, that it no longer remains conductive and the lamp becomes extinguished. 85 90 95

It is the object of my invention to over- 100

come or reduce to a minimum the foregoing difficulties encountered in the manufacture and use of the tubes and the electrodes, to the end that they may be more quickly and 5 economically produced in large quantities and will last indefinitely.

In the accompanying drawings: Fig. 1 shows one of the tubes in the course of construction.

10 Fig. 2 is a broken longitudinal section of one of the enlarged ends of the tube equipped with an electrode.

Fig. 3 is a cross section on line 3—3 of Fig. 2.

15 2 designates the glass tube which is provided at each of its enlarged ends with an inwardly projecting stem 4, the inner convex end of which may be slightly enlarged as indicated at 6 for the reception of an 20 electrode 8 consisting preferably of platinum and the back of which is sealed in said enlarged end 6 during the formation of the latter. The electrodes 8 are of concavo-convex form to add rigidity thereto and in order 25 that they may snugly fit the convex ends of the respective stems 4. Wires 10 lead outwardly to a suitable source, not shown from the respective electrodes 8 through the stems 4 in which said wires are hermetically 30 sealed.

During the formation of the tube 2 it is provided with a receptacle 12, to the neck 13 of which a pipe 14 is connected and equipped with a valve 16 and a hose 18, 35 which latter is adapted to be connected to a vacuum pump not shown. A branch 20 through which the gas neon is admitted is connected to the pipe 14 and provided with a valve 22 for controlling the flow of the 40 neon into the tube 2.

The tube 2 is charged with neon through which an electric current of approximately normal strength is transmitted for expelling the foreign gases from the glass walls and 45 the electrodes. The tube is also subjected to an external temperature of approximately 400 degrees F. to hasten the expulsion of the gases which are then removed from the tube through the action of the vacuum pump.

50 Any trace of foreign gases admitted with the neon to the tube 2 are absorbed from the latter by a suitable chemical such as anhydrous phosphorous pentaoxide with which the receptacle 12 is supplied. The tube 2 is then sealed where it joins the neck 13 and is separated from the receptacle 12, after 55 which it is ready for use.

The current used for liberating the occluded gases from the platinum electrodes 60 need not be so great as that used on other electrodes of less density because when heated to approximately 130 degrees C. the platinum is transformed into a catalytic agent, causing the combination of carbon 65 monoxide with oxygen to form carbon di-

oxide, which gases are readily removed through the operation of the vacuum pump and the application of external heat of approximately 400 degrees F. Neither is it necessary to prolong the treatment of the 70 platinum electrode as with copper and other electrodes, as the exposed area of the platinum electrode is considerably smaller and gives off only about one-tenth of its volume in occluded gases, whereas copper gives off about one-sixth of its volume in occluded gases when subjected to the same conditions. 75

When made of platinum the electrodes 8 need not have an exposed area of more than 1 square decimeter per ampere, because I 80 have found that platinum is far superior to copper, carbon and other materials heretofore used for electrodes as the platinum being less porous contains less of the detrimental gases and does not require the prolonged treatment to which the other electrodes must be subjected for the purpose of eliminating the impure gases. Furthermore, the exposed area of the platinum electrode need be but a small fraction of that 85 of other electrodes heretofore employed, thereby further reducing the volume of foreign gases to be eliminated. Also, owing to the density of the platinum less vaporization takes place during the passage of an 90 electric current and it will not be necessary to repeatedly admit neon to the tube for the purpose of scavenging the latter, as with other methods.

95 By eliminating the practice of using repeated charges of neon when scavenging the tubes during their formation a material saving of this expensive gas is effected. A further saving in the cost of manufacture is effected by employing anhydrous phosphorous pentaoxide for absorbing the foreign gases from the neon on the spot instead of using cocoanut charcoal in a receptacle which is immersed in liquid air to 100 reduce the temperature of the charcoal to a low enough degree to render it effective in absorbing the foreign gases.

Having thus described my invention, what I claim and desire to secure by Letters Patent, is:

In combination, a glass tube closed at each end, a solid stem formed integral with each end of said tube and extending into the latter, each stem having a convex terminal, a concavo-convex electrode fixed to the inner end of each stem, and a conductor 110 connected to each electrode.

In testimony whereof I affix my signature.
GEORGE E. TEASDALE.
